US00D848841S

(12) **United States Design Patent** (10) **Patent No.:** **US D848,841 S**
Fukumoto et al. (45) **Date of Patent:** **** May 21, 2019**

(54) **CONTAINER**

- (71) Applicants: **Kikkoman Corporation**, Tokyo (JP); **Yoshino Kogyosho Co., Ltd.**, Tokyo (JP)
- (72) Inventors: **Masashi Fukumoto**, Noda (JP); **Denmi Kuwagaki**, Noda (JP); **Keisuke Miyairi**, Tokyo (JP); **Satoshi Sakamoto**, Tokyo (JP)
- (73) Assignees: **Kikkoman Corporation**, Chiba (JP); **Yoshino Kogyosho Co., Ltd.**, Tokyo (JP)
- (**) Term: **15 Years**
- (21) Appl. No.: **29/614,173**
- (22) Filed: **Aug. 16, 2017**

Related U.S. Application Data

- (62) Division of application No. 35/500,773, filed on Sep. 30, 2015 (U.S. filing date under 35 U.S.C. 384), and having an international filing date of Sep. 30, 2015, now Pat. No. Des. 798,712.
